(57) **CLAIM**

The ornamental design for an exercise weight holder, as shown and described.

DESCRIPTION

FIG. 1 is a top right perspective view of an exercise weight holder showing our new design;

FIG. 2 is a bottom right perspective view thereof;

FIG. 3 is a left side rear perspective view thereof;

FIG. 4 is a front elevational view thereof;

FIG. 5 is a rear elevational view thereof;

FIG. 6 is a side elevational view thereof;

FIG. 7 is the opposite side view of FIG. 6.

FIG. 8 is a top plan view thereof; and,

FIG. 9 is a bottom plan view thereof.

The broken lines illustrate unclaimed portions of the article.
